MOTION PICTURE APPARATUS

Filed April 17, 1931

UNITED STATES PATENT OFFICE

ELLWOOD W. REYNOLDS, OF DREXEL HILL, PENNSYLVANIA, ASSIGNOR TO WESTINGHOUSE ELECTRIC & MANUFACTURING COMPANY, A CORPORATION OF PENNSYLVANIA

MOTION PICTURE APPARATUS

Application filed April 17, 1931. Serial No. 530,772.

My invention relates to web-handling apparatus and has particular relation to apparatus for regulating the speed of a web as it is advanced.

5 The present application is a continuation in part, of my co-pending application, Serial No. 436,552, filed March 17, 1930, and assigned to Westinghouse Electric and Manufacturing Company. Certain of the features 10 shown but not claimed in the present application are shown and claimed in my copending application, Serial No. 650,875, filed January 6, 1933 and in the following applications: Serial No. 406,847, filed November 13, 15 1928 to Clinton R. Hanna and Emil H. Greibach; Serial No. 461,274, filed June 16, 1930 to William Laudenbach and Francis Herdon; Serial No. 524,879, filed March 24, 1931 to Clinton R. Hanna; Serial No. 640,262, filed 20 October 29, 1932 to Clinton R. Hanna and Emil H. Greibach; Serial No. 663,377, filed March 29, 1933 to Clinton R. Hanna.

Apparatus for regulating the speed of a web, as it is advanced through a web-handling machine, such as a motion-picture machine, ordinarily comprises a low-pass mechanical filter which includes a resiliently mounted sprocket for advancing the web and an inertia roller rotated by the advancing 25 web. These mechanical filters are particularly applicable in photo-acoustic apparatus wherein it is highly desirable that a film strip be advanced at a substantially uniform speed.

30 In working with photo-acoustic apparatus, I have found that the filtering systems, constructed according to the teachings of the prior art, which comprise, as has been pointed out, a single resiliently mounted sprocket and a single flywheel, ordinarily occasion considerable difficulty. The flywheel should be of comparatively large inertia and, as a result, considerable tension is required in the film to rotate it uniformly. The expense involved in the provision of substantially frictionless bearings for the inertia roller is an item of no small importance. Moreover, in view of the fact that the ordinary film strip is not a highly elastic medium, it is deleteriously affected by tensional forces of ordinary 35 magnitude. These features, when combined,

render the problem of providing for the application of the necessary torque to the rotation of the inertial mass in the filtering system, a comparatively difficult one.

55 Certain attempts have also been made to bring the film strip into more intimate engagement with the surface of the inertial roller by providing a plurality of pressure rollers that engage the film and hold it in firm contact with the inertia roller. However, I have found that the pressure rollers, by the irregularity of their reaction of the film, introduce a distortion in the sound that is produced from a film strip passing through a machine of such structure.

60 It is, accordingly, an object of my invention to provide a mechanical filter for a web-handling system wherein the requisite inertia mass shall be rotated with facility.

65 Another object of my invention is to provide a mechanical filter for web-handling apparatus wherein the inertia mass shall be rotated with comparatively small tension in the web.

70 Still another object of my invention is to provide apparatus of the type wherein a large mass to be rotated shall be effectively coupled to a web without the aid of additional pad rollers or prohibitive tension.

75 A further object of my invention is to provide a mechanical filter for a web-handling system wherein a web is held in engagement with the inertial mass by the tension forces in the web.

80 A still further object of my invention is to provide a mechanical filter for a web-handling system wherein pad rollers are not required to hold the web in engagement with the inertial mass.

85 An incidental object of my invention is to provide a shoeless gate for film-handling apparatus.

85 A further incidental object of my invention is to provide web-handling apparatus wherein the web shall be engaged by a plurality of web-handling mechanisms on one of its surfaces only.

90 A still further incidental object of my invention is to provide photo-acoustic apparatus of a type wherein the film shall be ad-

vanced in such manner as not to be mechanically marred on the surface on which the acoustic waves are recorded.

More specifically stated, it is an object of my invention to provide web-handling apparatus of the type wherein a web shall be advanced smoothly and uniformly without being excessively tensioned or broken.

According to my invention, I provide a web-filtering system wherein the ordinary inertial mass utilized is broken up into individual parts instead of being contained in a single unit. That is to say, in apparatus constructed according to the teachings of my invention, a plurality of inertia rollers are utilized instead of a single web-driven inertia roller, and the sum of the inertias of these rollers is made equivalent to the necessary inertia of the single web-driving roller of the prior art.

The effective angle of contact between the web and the roller is thus increased considerably and may, in fact, attain a value greater than 360° . The increase in the angle of contact results in an increase in the effective coupling between the mass and the web and, consequently, in an increase in the longitudinal force that must be applied to the web before it will slip relative to the rollers.

In view of the fact that, in a plural-roller system, the inertia of each individual roller is considerably smaller than the inertia of the single roller of the apparatus of the prior art, considerable less tension in the web is required to initiate the rotation of the rollers embodied in my improved system. Moreover, since the weight of the individual rollers is smaller than the weight of the single roller, less tension is required in the web to overcome bearing friction and to maintain the rollers in a state of uniform rotation.

Since the web must be tensioned to a certain degree, as it passes over the rollers, I have provided a film-tensioning system comprising a plurality of resiliently mounted sprocket wheels. The sprocket wheels perform the combined functions of providing for the tensioning of the web and of preventing the irregularities of the mechanical elements of the machine and of the web from being introduced into the portion of the web that is required to move uniformly.

In the specific embodiment of my invention, I have provided a surface to support a web, on each side of which a resiliently mounted sprocket wheel is disposed. One of the sprocket wheels is disposed below the surface and, when driven through the resilient coupling, it advances the web.

The second sprocket wheel is disposed above the web-supporting surface and is rotated by the web. It is resiliently coupled to a damping device and, by reason of the damping, exerts a tension on the web. An

inertial roller is associated with each sprocket.

It is to be noted that, in view of the fact that the sprocket wheels are resiliently supported, the variations between the sprocket wheel pitch and the sprocket-hole pitch of the web is taken up in the coupling and is not transmitted to the web. Furthermore, by reason of the fact that the web-rotated sprocket wheel is resiliently mounted, the irregularities that may be present in the damping device are eliminated and do not appear in the motion of the web.

In one embodiment of my invention, the web-supporting surface is an ordinary skid that is stationary relative to the web. In a second embodiment of my invention, the web-supporting surface is a drum rotated by the web. It is understood, of course, that the drum may be equipped with an inertial mass and that, in consequence thereof, the necessary inertia may be divided between three masses instead of two, as is the case for the specific embodiments of my invention that will be described herein.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing, in which

Figure 1 is a schematic view, in front elevation, showing the essential elements of an embodiment of my invention;

Fig. 2 is a view, in section, taken along the line II—II of Fig. 1 and showing the mounting of the sprocket wheels utilized in my invention;

Fig. 3 is a perspective view, certain parts being broken away, showing a resiliently mounted sprocket wheel utilized in the practice of my invention, and

Fig. 4 is a schematic view, in front elevation, showing a modified embodiment of my invention.

The apparatus shown in Figs. 1, 2 and 3 comprises a plurality of web-engaging sprocket wheels 1, 3 and 4 to advance a web 5 over a skid 7. In view of the fact that my invention has been, in general, applied to photo-acoustic apparatus, it is shown in the present embodiment of my invention as applied in this field. Specifically, the web 5 is, therefore, a photo-acoustic film.

A section of the telescope 9 of a sound-reproducing optical system is disposed adjacent to the film 5, and a photo-tube 11, responsive to the variations in the light transmitted through the film 5, is disposed behind the film. The skid 7 is equipped with an aperture 13, through which the light from the

optical system is transmitted to the cell 11 and is commonly known as an aperture plate.

Fig. 2 may be regarded as an enlarged transverse section, taken along the line II-II of Fig. 1, with all the elements but the sprocket wheels 1 and 3 omitted for purposes of clarity.

The lower sprocket wheel 3 is rotatably supported on a shaft 15 that is driven, through a gear wheel 17, by a prime mover (not shown), it being coupled to the shaft by a spring 19 one end of which is fastened to a pin 21 that is rigidly secured to the shaft and the other end of which is rigidly secured to the sprocket wheel by a screw 23. The sprocket wheel 3 is provided with a slot 3a to receive the pin 21, whereby a limited rotative movement of the sprocket wheel on the shaft is permitted.

To prevent the free oscillation of the sprocket wheel 3, a damping washer 25 of suitable material, such as felt, is provided to be compressed between the sprocket wheel and a collar 27, rigidly secured to the shaft, by a spring 29 that engages the bearing 31, in which the shaft rotates, and one face 33 of the sprocket wheel.

The upper sprocket wheel 1 is rotatably supported on a sleeve 35 that is, in turn, rotatably mounted on a stud 37 secured in the main base 39 of the system. The sleeve 35 is resiliently coupled to the sprocket wheel 1 by a spring 40, in a manner similar to that in which the driven shaft 15 is coupled to its corresponding sprocket wheel 3 by the spring 19. The sleeve 35 is mechanically damped by a washer 41, of suitable material, that is compressed between the sleeve and a collar 43 and resiliently urged toward the sleeve by a flat spring 45 that, in turn, engages a second collar 47 rigidly secured to the stud 37. The collar 43 that is in engagement with the damper washer 41 is rotatably mounted on the stud 37 and is equipped with a pin 49 which engages the threads 51 of the stud.

The sprocket wheel 4 is, ordinarily, a hold-back sprocket wheel, disposed between the take-up reel (not shown) and the pulling sprocket wheel 3 and is rigidly secured on a driven shaft 53.

A plurality of rollers 55 and 57, to be film-driven, are associated with the sprocket wheels 1 and 3. The film between the sprocket wheels 1 and 3 is maintained in tension by reason of the fact that the motion of the upper sprocket wheel 1 is damped and offers a resistance to the force exerted by the driven sprocket wheel. By reason of its tensioned condition, the film 5 is held in intimate engagement with the rollers 55 and 57.

It is to be noted that the damping device would have a tendency to introduce distortions in the velocity of the film, if the resilient coupling 40 were not included between the damping means and the sprocket wheel 1.

By reason of the fact that the film is ten-

sioned, shoe plates are not necessary on the film-supporting surface, and one of the most difficult problems that has arisen in connection with photo-acoustic apparatus is substantially solved.

76

In Fig. 4, apparatus of a type comprising elements similar to those of Fig. 1 are shown. In this case, however, the film is supported on a drum 59. In photo-acoustic apparatus of this type, the sound is ordinarily taken off by allowing the section of the film 5, wherein the sound track is impressed, to project over the edge of the drum 59 and, by suitably disposing the optical telescope 9 and the photo-tube 11 relative to the film. In the apparatus illustrated in Fig. 4, the photo-tube 11 is shown as disposed within the drum.

75

In view of the fact that a substantial angle of contact between the drum 59 and the web 5 is necessary for proper operation, a plurality of web-deflecting rollers 61 are provided between the drum and the inertial rollers 55 and 57.

85

In the description given hereinbefore, my invention has been shown as embodied in a specific system and has been, as a matter of fact, essentially illustrated schematically. In ordinary web-handling apparatus and particularly in film-handling apparatus, certain refinements are introduced. It is understood that machines incorporating these refinements lie within the scope of my invention if they also incorporate the essential features of my invention, as described herein.

90

Moreover, it will be noted that certain modifications of the apparatus described herein are possible. It is apparent that my invention may be practiced in a system wherein both of the resilient sprocket wheels are driven. As a matter of fact, I have experimented with apparatus of this type and have found it to operate satisfactorily.

100

Another modification of my invention that is apparent is one wherein the lower sprocket wheel 3 is driven at normal speed, while the upper sprocket wheel 1 has a peripheral speed greater, by a slight amount, than the peripheral speed of the lower sprocket wheel. In apparatus of this type, the sprocket wheel 1 is ordinarily rigidly secured to its shaft. In a still further modification of my invention, the lower sprocket wheel may be rotated at a greater speed than the upper sprocket wheel which is, in turn, rotated at the normal speed of the web.

110

In a still further modification of my invention the resilient coupling between the web-driven sprocket wheel and its corresponding damping device is omitted. I have found that the operation of this embodiment of my invention is almost as satisfactory as the operation of the embodiment described hereinabove.

125

Finally, I have noted that, under certain conditions, the web-supporting surface 7 or

130

59, between the web-tensioning systems, may be entirely omitted, and the sound may be, in this case, taken-off as the film moves between an optical system and a photo-tube 5 suitably disposed. For this modification of my invention, an optical system having a small angular aperture is desirable.

Although I have shown and described certain specific embodiments of my invention, I 10 am fully aware that many other modifications thereof are possible. My invention, therefore, is not to be restricted, except insofar as is necessitated by the prior art and by the spirit of the appended claims.

15 I claim as my invention:

1. Web-advancing apparatus comprising resiliently mounted dentate means to engage a web, inertial means disposed adjacent to said dentate means, additional resiliently- 20 mounted dentate means to engage said web, inertial means associated with said last-named dentate means, and means disposed between said groups of inertial means and dentate means for supporting said web.

25 2. Web-advancing apparatus comprising dentate means to engage a web, inertial means disposed adjacent to said dentate means, additional dentate means to engage said web, inertial means associated with said last- 30 named dentate means, and means disposed between said groups of inertia means and dentate means for supporting said web.

3. Web-advancing apparatus comprising resiliently mounted dentate means to advance 35 a web, inertial means disposed adjacent to said dentate means to be rotated by said web, additional resiliently mounted dentate means to engage said web and inertial means associated with said last-named dentate means to 40 engage said web.

4. Web-advancing apparatus comprising resiliently-mounted dentate means to advance a web, inertial means disposed adjacent to said dentate means to be rotated by said web, 45 additional resiliently-mounted dentate means to be rotated by said web and inertial means associated with said last-named dentate means to engage said web.

5. Web-tensioning apparatus comprising 50 a shaft to be power-driven, a dentate roller resiliently coupled to said shaft, a dentate roller to be film driven, and damping means associated with said first-named dentate roller.

55 6. Web-tensioning apparatus comprising a dentate roller to be power-driven, a dentate roller to be web-driven, damping means associated with said last-named dentate roller and a resilient coupling between said last-named dentate roller and said damping means.

7. Web-tensioning apparatus comprising 65 a dentate roller to be power-driven, a stud disposed adjacent to said dentate roller, a sleeve rotatably supported on said stud, and

a dentate roller to be web-driven and resiliently coupled to said sleeve.

8. Web-tensioning means including a plurality of dentate-rollers, certain of said rollers being resiliently mounted, and at least one of said resiliently-mounted rollers being adapted to be web-driven. 70

9. Web-tensioning apparatus comprising a shaft to be power-driven, dentate means resiliently coupled to said shaft to engage a web, a stud spaced from said shaft, a sleeve rotatably supported on said stud, dentate means resiliently coupled to said sleeve to engage said web, damping means associated with said sleeve, and a surface disposed between said stud and said shaft to support said web. 75 80

10. In film handling apparatus means for impressing a record on a film strip or for translating a record impressed on a film strip, means for supporting said film strip in the region of said impressing means or said translating means, means for advancing said film strip over said film-supporting means, means, including a resilient element, to cooperate with said advancing means and with said film strip to maintain said film strip in tensioned condition, and means including a plurality of rollers to be film driven, said rollers having considerable inertia, to cooperate with said resilient element and said advancing means to maintain said film in uniform motion as it passes over said supporting means. 85 90

11. Web-tensioning apparatus comprising means for advancing a web, a dentate roller to be driven by said web as it is advanced, damping means to cooperate with said web-driven roller to resist the torque applied by said web and resilient coupling means mechanically interposed between said dentate 100 roller and said damping means to partially take up the force impressed on said web by the coaction of said web, said advancing means and said damping means and thereby to suppress irregularities introduced into said web by the coaction of said damping means and said dentate means. 110

In testimony whereof, I have hereunto subscribed my name this 3 day of April 1931.

115 ELLWOOD W. REYNOLDS.
